INVENTOR.

CHARLES FREDERICK WHIFFEN.
BY HIS PATENT ATTORNEYS

Mark & Clark

UNITED STATES PATENT OFFICE.

CHARLES FREDERICK WHIFFEN, OF RANDWICK, NEAR SYDNEY, NEW SOUTH WALES,
AUSTRALIA.INTERLOCKING, REINFORCING, AND FASTENING ELEMENT FOR CONCRETE AND LIKE
STRUCTURES.

Application filed June 4, 1921. Serial No. 475,051.

To all whom it may concern:

Be it known that I, CHARLES FREDERICK WHIFFEN, a subject of the King of Great Britain, residing at "Braeside," No. 19 Rae

5 Street, Randwick, near Sydney, in the State of New South Wales and Commonwealth of Australia, engineer and builder, have invented new and useful Improved Interlocking, Reinforcing, and Fastening Elements for Concrete and like Structures, of which the following is a specification.

10 This invention refers to interlocking, reinforcing and fastening elements for use, especially in building constructions of concrete, plaster, and the like, particularly of the kind in which moulded slabs are used for building up the walls and for use as reinforcements in piles, posts, beams, sleepers and the like moulded of concrete and the 15 like. The improved interlocking, reinforcing and fastening elements for concrete and like structures have been especially devised, in order that moulded slabs may be formed with fastening means whereby the cost of 20 building is reduced, the erection of building is facilitated and expedited, skilled labor may be dispensed with, and timber frames or framing, as required in casting solid walls, may be dispensed with, thus saving the cost 25 of such frames and of their manipulation.

30 Though the elements have been especially devised for use in building constructions they are serviceable and may be used as reinforcements in the manufacture of cementitious articles such as piles, posts, beams, sleepers and the like.

35 Interlocking, reinforcing and fastening elements, intended for vertical disposition, and referred to as "verticals" are made 40 from strips of sheet metal of any desired thickness, and to any desired widths and lengths. In transverse section, the verticals have a narrow web and a wide web each at right angles to the other. The narrow web 45 has a longitudinal corrugation at or near the junction of the webs and an outer flat edge. The wide web has its longitudinal edge inwardly set towards the narrow web at an acute angle (approximately of 45 degrees) to form a longitudinal hook or catch, and along its length a plurality of distanced slots, with or without tongues thereat, said 50 tongues being formed by stamping or cutting three sides of the slot commencing at the

junction of two main webs, and bending 55 the released portion of said wide web into the same plane as that of the flat edge of the narrow web.

60 Interlocking and reinforcing elements, intended for horizontal disposition, and referred to as "spreaders," are constructed similarly to the verticals just described, but with the longitudinal corrugation in the wide web instead of in the narrow web.

65 In order that a practical application of the invention may be readily understood, the same will now be described with reference to the drawings, accompanying and forming part of this specification, in which Figures 1 and 2 are elevations respectively 70 of a vertical, with the edge of the narrow web and the hook edge of the wide web both forward;

75 Figure 3 is a section on the line 3—3 in Figure 1;

Figures 4 and 5 are elevations, respectively, 80 of a spreader with the edge of the wide web and the hook of the narrow web both forward;

Figure 6 is a section on the line 6—6 in Figure 4;

Figures 7 and 8 are front and end elevations, respectively, of a tie;

85 Figures 9 and 10 are elevation, and section, respectively, of a spreader, with a section of tie therethrough as a stiffener;

90 Figures 11 and 12 are similar views of a spreader being threaded through a vertical, and Figures 13 and 14 are similar views of the elements in locked position.

95 A vertical has a narrow web 15 with longitudinal corrugation 16 therein and flat edge 17 thereon, and a wide web 18 with pieces cut and pressed therefrom to form slots 19 having enlargements or clearances 20 and 95 tongues or abutments 21 at right angles thereto and in the plane of the flat edge 17; and its edge turned back towards the narrow web 15, to form longitudinal hook 22.

100 A spreader has wide web 23 with longitudinal corrugation 24 therein and flat edge 25 thereon, and a narrow web 26 with pieces cut therefrom to form slots 27, or the pieces are cut and pressed therefrom to form the 105 slots 27 and tongues 28 at right angles thereto and in the plane of the flat edge 25 of the web 23. The narrow web 26, preferably, has its edge turned back towards the wide

web 23 to form longitudinal hook 29, and has at desired points transverse slits or saw cuts 30 across said hook 29 and through part of the width of said narrow web 26, 5 so that when a spreader has been threaded through the slots 19, in the verticals, the enlargements 20 of said slots 19, allow for the passage of the hooks 29 of the spreader until the cuts 30 reach the webs 18 of the 10 vertical. At this time the cuts 30 may be slid along the webs 18 until the webs 26 engage the ends of the slots 19, as shown in Fig. 14, and thus lock the elements together.

A convenient tie 50 (illustrated in Figures 15 7 and 8) for use with the elements, has each longitudinal edge turned over upon the same side to form longitudinal hooks 51, but if desired, a tie with its longitudinal edges turned over upon opposite sides to form longitudinal hooks, may be used. From Figs. 9 and 20 10 it will be seen that the tie members are adapted to be inserted through the slots 27 of the horizontals.

In the preferred construction of the 25 spreader 23 the narrow web has the longitudinal hook 29 formed thereon, though this is not essential, and said web may have along its length a plurality of distanced slots 27 with or without tongues 28 thereat, said 30 tongues being formed as before stated.

Transverse slits or saw cuts 30 are made in said narrow web at the desired distances along its length and through about one third its width, said slits being through the longitudinal hook or catch 29 when same is formed on the web.

These slits are entered by the edges of the webs 18 which form a portion of the boundary of the slots in the verticals, and when 40 the spreaders have been threaded through said slots 19 and moved sidewardly to one end thereof, the verticals and spreaders are interlocked.

A reenforcing frame may be made up of 45 verticals 15 placed at suitable distances apart, and firmly connected together by means of the spreaders 23, and, if desired, the metal slats or stiffeners 50 (preferably with turned over edges 51), may be threaded through slots 27 in said spreaders between the verticals.

The slabs (not shown) are cast or moulded in moulds of any suitable size, about the elements or frames of assembled elements in 55 such manner, that the longitudinal hooks 22 on the "verticals" are left protruding from one face of the finished slab.

In casting or moulding a slab, the mould is supplied with a layer of material, the re-enforcing frame (made up of verticals 15 and spreaders 23 and, if desired, with slats 50 threaded through the latter as stiffeners) with the narrow webs of the verticals downwards is laid upon such layer, the hook edge 60 65 22 of the wide webs 18 being upwards above

the top of the mould, and a small space about one quarter of an inch being left between the ends of the elements and the sides and ends of the mould, which is then filled up to the required thickness with compo and faced off, the reenforcing frame thus being embedded but with the hook edges 22 of the verticals protruding clear of one face of the slab.

In another method of casting a slab, the 75 reenforcing frame with the hook edges 22 of the parallel verticals downwards has fillers (say of wood) fitted neatly between said parallel verticals and upon and covering the then upturned hook edges thereof, and is 80 then placed in the mould with said hook edges of the verticals downwards and resting upon the bottom of the mould, which is then filled up with compo and faced off, the reenforcing frame thus being embedded but 85 with the hook edges of the verticals protruding from one face of the slab.

A reenforcing frame of assembled elements, (preferably, spreaders vertically disposed with stiffening slats threaded horizontally through their slots) may, if desired, be applied to sheets of cement, fibrous plaster, or gypsum, now used in building construction, in order to provide an expeditious, inexpensive and effective reenforcing of such 90 sheets and means for fastening them on timber studding.

To apply the frame, the prepared sheet of such material is placed on a table or level surface, the upper face is thoroughly moistened with water, the frame with wide webs downwards is placed upon said sheet in alignment with the edges thereof, and with the ends of the stiffeners projecting beyond those edges (which will be the vertical edges 105 of the sheet) sufficiently to enable the said ends to give a good seating on timber studding.

The frame is then covered with compo, 110 preferably of a kindred substance to the sheet or of cement mortar, and same is allowed to dry and season, when the reinforced sheet is ready for use.

In the construction of buildings with cavity walls, parallel rows of slabs are positioned vertically in tiers, apart from one another the distance of the required cavity, and with their protruding hooks or catches 22 facing one another, (that is inwardly of the wall), slabs of requisite height and length 120 being used to provide openings for windows and doors where desired. The slabs are then tied together by means of ties, made from sheet metal to the desired width and length, and with a longitudinal hook along each 125 edge (either on the same side or upon opposite sides) said hooks being threaded within the protruding hooks 22 of the slabs in vertical line. This may be done as each course is erected, or upon completion of the wall to 130

the required height. Studs are cast or moulded around the ties the whole height of the cavity wall by placing a mould board or wedge upon each side of the ties within the cavity and then filling the vertical mould so formed, with selected material.

Piles, posts, beams, sleepers and the like, may be moulded around a frame of assembled elements having slots near each end, 10 and, if desired, at intermediate points, the verticals being disposed longitudinally and arranged to the sectional formation desired, (say circular, rectangular, etcetera), a spreader or plurality of spreaders being 15 threaded through and locked in said slots.

In lengthy construction, lengths of verticals are overlapped, and a spreader or plurality of spreaders threaded through and locked in the coincident slots in said overlapped ends, and at other points as desired. 20

I claim—

1. An interlocking, reenforcing and fastening element, or "vertical" for moulded concrete slabs and the like, having a narrow web with a longitudinal corrugation therein and a flat edge portion, and a wide web arranged at right angles to the narrow web and provided with slots therethrough having enlarged portions, and a longitudinal hook arranged at the free edge of said wide web. 25

2. An element as claimed in claim 1 having tongues extending from one edge of said slots and arranged in the same plane as the flat edge portion of the narrow web.

3. An interlocking and reenforcing element, or "spreader" for moulded concrete slabs or the like having a wide web with a longitudinal corrugation therein and a flat edge portion, and a narrow web arranged at 30 right angles to the wide web and having spaced slots arranged at its free edge.

4. An element as claimed in claim 3 in which the narrow web is provided with spaced slots adapted to receive stiffening elements. 45

5. An element as claimed in claim 3 in which the narrow web is provided with a series of spaced slots, and tongues extending outwardly from the slotted portions of said

narrow web and arranged in the same plane 50 as the flat edge portion of the wide web.

6. An element as claimed in claim 3 in which the free edge of the narrow web is provided with a longitudinally extending hook through which the slits extend. 55

7. In a reenforcing frame for molded concrete slabs and the like, a vertical element having a narrow web with a longitudinal corrugation therein and a flat edge portion, said vertical element having a wide web arranged 60 at right angles to the narrow web and provided with spaced slots having enlarged portions, the free edge of said vertical element being provided with a longitudinally extending hook, and a horizontally extending element cooperating with the vertical element and including a wide web with a longitudinal corrugation therein and a flat edge portion, said horizontal element also having a narrow web arranged at right angles to the wide 65 web and provided with spaced slits at its free edge, said horizontal element being threaded through one of the slots in the vertical element, and one of the slits in the horizontal element engaging a portion of the 70 wide web of the vertical element for locking said elements together.

8. In a reenforcing frame for moulded concrete and the like, a vertical element having a longitudinal corrugation and a longitudinally extending hook, said vertical element being also provided with a slot, and a horizontal element threaded through the slot of the vertical element and interlocking with the slotted portion of the vertical element. 75

9. In a reenforcing frame, a horizontal element having a longitudinally extending corrugation and a flat edge portion, a narrow web arranged at right angles to the flat edge portion and terminating in a longitudinally 80 extending hook, a slot provided in the narrow web, and a stiffening element extending through said slot and bearing upon the flat edge portion of said horizontal element.

Dated this third day of May, one thousand 95 nine hundred and twenty one.

CHARLES FREDERICK WHIFFEN.
